SWITCHING DEVICE

Frans Hendrik de Jong, Eindhoven, Netherlands, assignor to N. V. Philips' Gloeilampenfabrieken, Eindhoven, Netherlands

Application June 15, 1936, Serial No. 85,372
In Germany July 5, 1935

7 Claims. (Cl. 175—363)

My invention relates to switching devices, and more particularly to switching devices for controlling a plurality of circuits in time sequence.

My invention is particularly adapted for controlling the cathode heating circuit and d. c. load circuit of gas-filled rectifiers, and I shall describe same in this connection, although its use is not limited thereto.

To prevent premature loading of the cathode 10 of a gas-filled rectifier with emission current, it is desirable, and in many cases imperative, that the anode voltage be not applied until the cathode has been heated to a certain predetermined temperature. For this purpose, numerous 15 switching devices have been proposed which in general operate according to two methods. The first method merely uses a manual switch for the cathode heating current and a manual switch for the d. c. load circuit; whereas the second 20 method uses a manual switch for the cathode heating circuit, and a time-delay device which automatically closes the d. c. circuit after a predetermined time interval.

Such switching devices however, have the disadvantages that they either do not provide the proper protection or are large, expensive, and complicated. For instance, when merely using two manually-operated switches, the possibility always exists that the operator might prematurely 25 close the direct current switch and thus apply the anode voltage before the cathode has reached its proper temperature. Although the automatic devices operating according to the second method prevent any errors due to the human element, 30 such devices are expensive and complicated, due to the fact that an automatic time-delay, as well as one or more auxiliary relays or contactors must be provided for each rectifier.

The object of my invention is to eliminate the 40 above disadvantages and to provide for this purpose a semi-automatic switching device which is of inexpensive and simple construction, and which completely protects the rectifier from premature application of the anode voltage.

In accordance with the invention, I provide 45 manual switches to control the a. c. and the d. c. circuits, and mechanically interlock these switches in such a manner that the d. c. switch cannot be closed within a predetermined time 50 after the a. c. switch has been closed, and that the a. c. switch cannot be opened until after the d. c. switch has been opened.

More particularly, I provide an electrically- 55 actuated mechanical interlock between the two switches, and control the movement of this in-

terlock by a time-delay device, preferably of the bimetallic type, whereby, at a predetermined time interval after closure of the a. c. switch, the d. c. switch is unlocked and the a. c. switch is locked in its closed position. As an interlock I prefer 5 to use a locking member so arranged between co-operating members of the a. c. and d. c. switches that the a. c. switch is locked in its closed position when the direct current switch is in its closed position, and the d. c. switch is locked in its open 10 position when the a. c. switch is open.

I prefer to use manual switches of the rotary-type as this allows the interlocking to be effected in a very simple manner by means of a slidable rod-shaped locking member cooperating with indentations in rotatable members of the switches and moved by an electromagnet into that position in which the direct current switch is unlocked. 15

In order that my invention may be clearly understood and readily carried into effect, I shall 20 describe same more fully with reference to the accompanying drawing, in which:

Figure 1 is a schematic view partly in perspective of a switching device according to the invention, and 25

Figure 2 is a perspective view of a device according to the invention.

The switching device shown in Figure 1 is used 30 for controlling the a. c. and d. c. circuits of a single-phase gas-filled rectifier 30, and comprises an a. c. rotary manual switch B, a d. c. rotary manual switch C, a time-delay device A, and an electrically-actuated mechanical interlock D. 35

The switch B comprises a manually-operated shaft 45 upon which are secured a commutator 46, and a rotatable disc-shaped member 1 provided on its periphery with two diametrically-opposite indentations 43. The commutator 46 40 comprises a cylinder of insulating material provided with two conductive segments 34 adapted to shunt stationary contact fingers 36—37, and contact fingers 38—39 respectively.

The switch C is similar in construction to the 45 switch B, and comprises a manually-operated shaft 47 carrying a rotatable member 2 having two diametrically-opposite grooves 4, and a commutator 48 of insulating material provided with two conductive segments 35 adapted to shunt 50 stationary contact fingers 40 and 41.

Slidably supported between members 1 and 2 and movable in the plane thereof so that its ends can enter the grooves 43 and 4 respectively is a rod-shaped member 3 having a portion 60 of 55

magnetic material and carrying a movable contact 16, which in the position shown cooperates with a stationary contact 51. Surrounding the rod 3 to the left of the portion 60 is a solenoid 5 coil 5, which serves to move the rod in the direction of the arrow.

A source of alternating current to be rectified is connected across terminals 10 and 11, connected to contact fingers 36 and 39 respectively 10 of switch B. Contact 37 is connected to one terminal of the primary winding of a cathode heating transformer 31, whose other end is connected to the contact 38 whereby switch B controls the heating of the cathode 62 of tube 30.

15 The anode 63 of rectifier 30 is connected through a d. c. load 44 to contact finger 41; contact finger 40 being connected to terminal 10. Thus switch C controls the d. c. circuit of the tube.

20 The time-delay device A, which is of the thermal type, comprises a stationary contact 19 having a terminal 22, and a bimetallic strip 58 carrying a movable contact 18 and surrounded by a heating coil 61. Coil 61 has one end connected 25 through a current-limiting resistance 17 to the contact 51, and its other end connected to contact 18 at 24 and to finger 37 of switch B. Thus, energization of coil 61 is controlled by contacts 16—51 and by fingers 38—39 and 36—37 of 30 switch B.

With the device in its off-position as shown, the right hand end of rod 3 extends into the groove 4 to thereby prevent movement of shaft 47 and closure of the d. c. circuit whereas switch

35 B is unlocked. To place the device in operation, shaft 45 is rotated clockwise or counterclockwise through an angle of 90° whereby segments 34 shunt fingers 36—37 and fingers 38—39 respectively, to thereby energize transformer 31 and 40 initiate heating of the cathode 62.

At the same time coil 61 is energized through a circuit including terminal 10, fingers 38—39, conductor 53, contacts 16 and 51, resistance 17, coil 61 and back through fingers 36—37 to terminal 45 10. After a predetermined time interval, depending upon adjustment of the time device A, contact 18 touches contact 19 and closes the circuit of coil 5, which circuit may be traced from contact finger 38, through coil 5, conductor 50, 50 contacts 19 and 18, point 24 and back to contact finger 37. Energization of coil 5 moves rod 3 in the direction of the arrow, whereby its left-hand end enters the indentation 43 (indicated by dotted lines), and its right-hand end leaves the 55 groove 4 to unlock switch C. At the same time the energizing circuit of coil 61 is interrupted by the breaking of contacts 16 and 51, whereby the bimetallic strip 58 is allowed to cool, contacts 18 and 19 break, and coil 5 is deenergized.

60 Switch C, being unlocked, can now be rotated through 90° whereby one of the contact segments 35 bridges contact fingers 40 and 41 to close the d. c. circuit. Upon rotating switch C from the 65 position shown, the peripheral surface of member 2 cooperates with the right hand end of rod 3 to prevent its movement to the right and thus switch B is locked in its closed position.

To place the device out of service, switch C is first returned to the position shown, thereby 70 interrupting the d. c. circuit, and bringing one of the grooves 4 into alignment with the right-hand end of rod 3. Switch B may then be returned to the position shown whereby the a. c. circuit is interrupted, rod 3 is moved to the right,

and the device assumes the position shown in the figure.

The construction of a device according to the invention is illustrated in Fig. 2, in which parts corresponding to those of Fig. 1 are given the same reference numerals. The device shown in Fig. 2 comprises a sheet metal frame 70 upon which are mounted the various parts of the device. The switches A and B of Fig. 1 are only partly shown and are indicated by their shafts 45 and 47. The rod-shaped locking member 3 is disposed in the same plane as the parallel axes of shafts 45 and 47, but perpendicularly thereto so as to be axially slidable and to be capable of engaging the indentations 4 and 43 in the manner above described.

In Fig. 2, the means for moving the rod 3 to the left comprises a stationary core formed of two bundles 25 and 26 of E-shaped laminations, a coil 5, and an armature formed of two bundles 20 of laminations 27 and 28 secured to the rod 3. The locking rod 3 passes through the space formed between the two bundles 25 and 26 and carries the contact 16 which cooperates with the contact 51 insulatingly mounted on the frame 70. 25

Upon energization of coil 5, and with shaft 45 rotated 90° from the position shown, the movable armature 27—28 is attracted by the core 25—26 in the direction of the arrow, whereby locking member 3 is moved into its left-hand 30 position and the auxiliary contact 16 is opened. In this position, as stated above, it is possible to turn the shaft 2 into the closed position of switch C.

35 Mounted on the top of the container is the current limiting resistance 17 and the bimetallic relay A. As shown, the relay A is mounted within a glass envelope provided with a base which is inserted in a standard socket, however it may be of various other types and constructions which 40 are well known in the art.

While I have described my invention in connection with specific examples and applications, I do not wish to be limited thereto, but desire the appended claims to be construed as broadly as 45 permissible in view of the prior art.

What I claim is:

1. A switching device for controlling two circuits comprising a manually-operated switch for controlling one circuit, a second manually-operated switch for controlling the second circuit, and means to make said first switch operative after a predetermined time interval after closure of said second switch and to prevent opening of said second switch while said first switch is closed, said means comprising a movable interlocking member cooperating with said switches to mechanically lock same, electromagnetic means for moving said member to unlock said first switch, and means including a time-delay device to energize 60 said electromagnetic means at a predetermined time after closure of said second switch.

2. A switching device for controlling two circuits comprising a manually-operated switch for controlling one circuit, a second manually-operated switch for controlling the second circuit, and means to make said first switch operative after a predetermined time interval after closure of said second switch and to prevent opening of said second switch while said first switch is closed, 65 said means comprising a movable interlocking member cooperating with said switches to mechanically lock same, electromagnetic means for moving said member to unlock said first switch, and means including a thermal time-delay relay 75

to energize said electromagnetic means at a predetermined time after closure of said second switch.

3. A switching device for controlling two circuits comprising a manually-operated switch for controlling one circuit, a second manually-operated switch for controlling the second circuit, and means to make said first switch operative after a predetermined time interval after closure of said second switch and to prevent opening of said second switch while said first switch is closed, said means comprising, a movable interlocking member cooperating with said switches to mechanically lock same, and electromagnetic means including a bimetallic time-delay device to energize said electromagnetic means at a predetermined time after closure of said second switch.

4. A switching device for controlling two circuits comprising a manually-operated rotary switch for controlling one circuit, a second manually-operated rotary switch for controlling the second circuit, and means to make said first switch operative after a predetermined time interval after closure of said second switch and to prevent opening of said second switch while said first switch is closed, said means comprising operating members rotatable with said switches and provided with locking indentations, a rod-shaped interlocking member cooperating with said indentations to mechanically lock said switches, electromagnetic means for moving said member to unlock said first switch, and means including a time-delay device to energize said electromagnetic means at a predetermined time after closure of said second switch.

5. A switching device for closing the anode circuit of an incandescent cathode rectifier at a predetermined time after closure of the cathode heating circuit comprising a manually-operated switch for controlling the anode circuit, a second manually-operated switch for controlling the cathode heating circuit, and means to make said first switch operative after a predetermined time after closure of said second switch and to prevent opening of said second switch while said first switch is closed, said means comprising a movable interlocking member cooperating with said switches to mechanically lock same,

electromagnetic means for moving said member to unlock said first switch, and means including a time-delay device to energize said electromagnetic means at a predetermined time after closure of said second switch.

6. A switching device for closing the anode circuit of an incandescent cathode rectifier at a predetermined interval after closure of the cathode heating circuit comprising a manually-operated rotary switch for controlling the anode circuit, a second manually-operated rotary switch for controlling the cathode heating circuit, and means to make said first switch operative after a predetermined time interval after closure of said second switch and to prevent opening of said second switch while said first switch is closed, said means comprising operating members rotatable with said switches and provided with locking indentations, a movable interlocking member cooperating with said indentations to mechanically lock said switch, electromagnetic means for moving said interlocking member to unlock said first switch, and means including a thermal time-delay relay to energize said electromagnetic means at a predetermined time after closure of said second switch.

7. In combination, a gas-filled rectifier tube having an incandescent cathode and an anode, and a switching device for preventing application of the anode voltage before the cathode has been heated to a predetermined temperature, said device comprising a manually-operated switch for controlling the anode voltage, a second manually-operated switch for controlling the heating of the cathode, and means to make said first switch operative after a predetermined time interval after closure of said second switch and to prevent opening of said second switch while said first switch is closed, said means comprising a movable interlocking member cooperating with said switches to mechanically lock same, electromagnetic means for moving said member to unlock said first switch, and means including a time-delay device controlled by said second switch to energize said electromagnetic means at a predetermined time after closure of said second switch.

FRANS HENDRIK DE JONG.
